ATTORNEY

UNITED STATES PATENT OFFICE.

FREDERICK H. WAPPLER, OF FLUSHING, NEW YORK, ASSIGNOR TO WAPPLER ELECTRIC COMPANY INC., OF LONG ISLAND CITY, NEW YORK, A CORPORATION OF NEW YORK.

CLAMPING ELECTRODE.

Application filed April 6, 1925. Serial No. 20,898.

My invention relates to clamping electrodes of the type in which there is an electrode clamp so formed and arranged as to be capable of adjustment within wide limits and for different purposes, and provided with electrodes through which current is passed through various parts of the human body.

My device is suitable for various medical and therapeutical uses, in connection with electric currents of different kinds, and particularly with high frequency currents and with constant and induced currents.

More particularly stated, my invention contemplates an electrode clamp so formed and arranged that with the electrodes mounted upon it and ready for use it is as a whole suitable for automatically holding itself and the electrodes in position upon practically any predetermined part of the human anatomy, or in other words, is self-clinging, and is yet so constructed and operated as to be capable of a large number of adjustments.

My improved clamping electrode is so constructed and arranged that, with the electrodes which it carries, it may be opened and closed somewhat after the manner of a pair of tongs, and yet may be so adjusted that the electrodes are very close together or very wide apart as the case may be, this adjustment of the electrodes being independent of the pivotal or tongs-like movement of the device.

My device is also suitably arranged for using the two electrodes as bipolar electrodes or connecting them directly together for use as a unipolar electrode.

My device is relatively simple in construction, easy to manufacture and made of parts readily standardized. It occupies comparatively small space and is light in construction, as well as easy to handle in practice.

Reference is made to the accompanying drawing forming a part of my specification, and in which like reference characters indicate like parts throughout the several figures.

Figure 1 is a side elevation of one form of my device, certain parts being shown as broken away.

Figure 2 is a section on the line 2—2, of Figure 1, looking in the direction indicated by the arrows.

Figure 3 is a side elevation of another form of my device, certain parts being shown as broken away.

Figure 4 is a fragmentary plan view of the form of my device shown in Figure 3.

Figure 5 shows the form of my device appearing in Figure 3, but with certain movable parts adjusted into positions different from the positions they occupy in said Figure 3, and the electrodes being thus brought more closely together.

Figure 6 is a side elevation showing the form of my device appearing in Figure 1, but with the electrodes adjusted askew relative to other parts for accommodating the device to a particular part of the anatomy.

Figure 7 is a side elevation showing the form of my device appearing in Figure 1, but with the electrodes adjusted askew relative to other parts to adapt the device to a different position than that contemplated by Figure 6.

I will first describe the form of my device appearing in Figures 1 and 2:

A pair of arms 8, 8, made of insulating material are formed alike and each provided with a slot 9, shown more particularly in Figure 2, this slot extending lengthwise of the arm. Mounted upon each arm 8 is an electrode 10, having the general form of a flat plate, slightly curved. Each arm is carried by a corner 11 of metal and secured to the latter by a bolt 11^a.

Extending through the corner pieces 11 are bolts 12 provided with threaded portions 13, and revolubly fitted upon these bolts are milled nuts 14 adapted to be turned by hand. Adjustably connected with the corner pieces 11 by means of the bolts 12 and milled nuts 14 are a pair of supporting arms 15. These supporting arms are exactly alike and are each provided with a slot 16, as shown at the right of Figure 1. The adjacent bolt 12 extends through this slot 16, and with the adjacent corner piece 11 and parts carried thereby is slidably back and forth upon the supporting arm 15.

Connected with the supporting arms 15, 15, are a pair of handle pieces 17, 17, each handle piece 17 being practically a continuation of the adjacent supporting arm 15.

A coiled spring 18 is provided with a pair of end portions 19 which engage the adjacent handle pieces 17 and tend to force the latter apart, as may be understood from Figure 1. This coiled spring 18 encircles a rivet 20 of tubular form. This rivet is secured rigidly to a yoke 21 and extends loose-

ly through another yoke 22. By this arrangement the yokes 21 and 22 are adapted to rock slightly in relation to each other; or in other words, the yoke 22 rocks upon the rivet 20, which is immovable relative to the yoke 21.

It will be noted that, with the various parts occupying the positions indicated for them in Figure 1, the portion of the yoke 21 at the right of the rivet 20 is engaged and pressed against the adjacent edge portion of the yoke 22, and acts as a limiting stop. Thus while the spring 18 by its tension has a tendency to rock the yokes 21 and 22 in opposite directions upon the axis of the rivet 20 as a center, the limiting stop just mentioned normally holds the yokes 21 and 22 in the positions indicated for them in Figure 1, except when the handles 17, 17 are moved toward each other.

It is obvious that except when the handles 17 are pressed toward each other, the supporting arms 15 extend in exactly opposite direction, and consequently that the arms 8, 8 are strictly parallel with each other, as indicated in Figure 1.

The action of the form of my device appearing in Figure 1 may be readily understood from the foregoing description.

30 The operator, by grasping the handles 17, 17 and pressing them toward each other, causes the yokes 21 and 22 to rock relatively to each other; so that the arms 8, 8, of insulating material swing angularly further apart, carrying with them the electrode plates 10, 10, these plates being thus moved further apart, and tilted to different angles. By releasing the pressure upon the handles 17, the operator causes the pressure of the 40 spring 18 to shift the yokes 21 and 22 back into their relative normal positions, the arm 8, 8 and parts carried thereby being by this movement restored to the respective positions indicated for them in Figure 1.

45 The form of my device appearing in Figure 3 differs slightly from that appearing in Figure 1, as I will now explain. In the construction shown in Figures 3 and 4 are two arms 23, 23, each L-shaped and made of metal, and each provided with a slot 24, corresponding in general function to the slot 9 shown in Figure 2. Each arm 23, 23 is provided with a portion 25, through which extends a screw 26, this screw having a threaded portion 27 which extends through a hole in the portion 25 and is fitted with a revolute milled nut 28.

50 The screw 26 also extends through a slot 30 in a supporting arm 29, as may be understood from Figure 4. There are two of these supporting arms 29, each made of insulating material, and each has the form of a flat bar.

55 A pair of handles 32 are made of metal and provided respectively with portions 32a

bent in opposite directions as indicated in Figure 3, these portions being secured rigidly to the adjacent end portions of the supporting arm by means of rivets 32b. The arms 32 are provided with portions 33 and 34, formed into yokes and pivotally mounted in connection with the spring 18, as above described with reference to Figures 1 and 2.

With either form of my device the electrode plates 10, 10 are mounted upon threaded bolts 36, which extend through the slots 9 or 24, as the case may be, of the supporting arms 8 or 23. Revolubly fitted upon the threaded bolt 36 is a milled nut 37, carrying a split stem 38 of tubular form. There are 75 two of these stems exactly alike, and fitting into each is a pin 40 constituting the tip of a conducting cord 41. Electric currents are supplied to the electrodes 10 through these conducting cords 41, in the usual or any 80 desired manner.

While in either form of my device the electrode plates are arranged as bipolar electrodes, they can in either instance be made to 90 serve together as a unipolar electrode by connecting them together by a short piece of wire, not shown, in the manner well known in this art.

Again, it is obvious that the arms 23, 23 and parts carried thereby as shown in Figure 3 may be substituted for the corner pieces 11, 11 shown in Figure 1, and the devices thus used as a single pole clamping electrode.

95 Except as stated, the construction and action of the form of my device shown in Figure 3 is like that appearing in Figures 1 and 2.

With either form above described, the device has a wide range of adaptability and 105 can be so adjusted as to move the electrode plates 10, 10 close together, in a substantially straight line, or to leave them a considerable distance apart, while at the same time allowing them to be moved angularly, 110 under control of the handles.

With the electrode plates 10, 10 and parts 115 immediately associated therewith arranged as indicated in Figures 1 and 2, the electrodes can be brought into engagement with opposite sides of a rather large or thick anatomical member such as a thigh, the neck, or the torso and yet the relative positions of the electrode plates 10 can be shifted angularly, like the blades of a pair of scissors. Thus any required spacing, within the limits of adjustability of the apparatus, can be 120 made between the electrode plates, although the latter are normally held in such position that the metallic arms 23 are parallel with each other; and with the electrode plates thus spaced apart, they can still be shifted to different angles relatively to each other, by pressing the handles toward each other, as above described.

In some instances it may be desirable to bring the electrode plates 10, 10 rather close together, in order to put them upon opposite sides of an anatomical member, such as a 5 forearm, a wrist, or even a finger. For this purpose the arms 8, 8, or 23, 23 as the case may be, are each turned around and the electrode plates 10 are taken off these arms and turned around relatively toward them, so that the electrode plate 10, 10 will still 10 face each other and yet be closer together, as indicated in Figure 5. In this figure the electrode plates are shown as fitted against opposite sides of an anatomical member 35, such as an ankle or a forearm, and which is 15 of relatively small size.

To change the device shown in Figure 3, so that it may be used as indicated in Figure 5, is thus a matter of simple adjustment.

Again, it may sometimes happen that in 20 using either form of the device it may be desirable to shift the electrode plates 10, 10, into such positions, relative to the supporting arms carrying them, that their handles 32, 32 25 will extend in some direction convenient for them to be grasped by the operator. This purpose is accomplished in the manner which may be understood by an inspection of Figure 6. As may be seen from this figure, the 30 electrode plates are so positioned relatively to the other parts of the device that they may be readily fitted upon the anatomical member 35 in practically any position the latter may occupy, and yet so that the handles 32 extend in such direction as to enable them to be readily grasped by the 35 operator.

In the clamping electrodes heretofore used, the electrode plates have been adjustable angularly, like the blades of a pair of scissors, but have not been adjustable toward and from each other by movements in straight lines. The result was that whenever such a clamping electrode was used successively upon anatomical members of different sizes, such as the wrist, ankle, neck and thigh, the electrode plates were shifted to successively different angles relatively to each other, and the distribution of the current 40 and the length of its path was varied accordingly, with bad results. If a given electrode clamp with its pair of electrode plates were placed upon one anatomical part the distribution of current might be 45 satisfactory, but with the device shifted to a larger or smaller anatomical member, the current would flow too freely at one point and not freely enough at another. The result was that some part of the body treated would 50 become overheated, and there was danger of burning the patient, and the distribution of the electric current was rendered erratic and impossible to control.

By my invention these troubles are avoided, or greatly reduced.

The electrode plates here shown are merely typical, as the electrodes actually employed in practice may be of any of the known forms for applying current to the body, and as pads, ohmless electrodes, conductive cushions, etc.

I do not limit myself to the precise construction shown, as variations may be made therein without departing from my invention the scope of which is commensurate with my claims.

I claim:

1. In a clamping electrode, the combination of a pair of supporting arms, a pair of electrode plates each carried by one of said arms, means for applying electric currents to said arms, handle members connected with said arms and controllable by the operator for causing said arms to move apart, spring mechanism connected with said arms for forcing them toward each other, and mechanism independent of said spring mechanism for enabling the operator to vary the distance between said electrode plates.

2. An electrode clamp comprising a pair of arms pivotally connected together, a pair of electrodes insulated from each other and each carried by one of said arms, a pair of handle members connected with said arms for shifting the relative positions thereof in one direction in order to vary the distance between said electrode plates, means for retracting said arms into predetermined normal positions, and mechanism connected within said arms and controllable by the operator for further varying the distance apart of said electrode plates.

3. A device of the character described, comprising a pair of arms pivotally connected together and thus mounted to swing angularly upon a pivotal center, a pair of electrode plates mounted upon said arms, mechanism controllable by the operator for shifting said arms angularly upon said pivotal center in order to move the electrode plates angularly apart, spring mechanism for automatically shifting the arms toward each other in order to bring said electrode plates into different angular positions relatively to each other, and adjustment mechanism connected with said arms and controllable by the operator for varying the distance of said electrode plates from said pivotal center.

4. In a clamping electrode the combination of a tubular pivot, a pair of yokes journaled upon said tubular pivot, spring mechanism connected with said yokes, and with said pivot for the purpose of rocking said yokes into predetermined relative positions, a pair of arms connected with said yokes, a pair of electrode plates carried by said arms, mechanism controllable by the operator for virtually lengthening and shortening said arms, and means for energizing electrode plates.

5. An electrode clamp comprising a pair of supporting arms each provided with a slot, a pair of electrode plates mounted upon said supporting arms, and each provided with a portion extending through said slot, so that said electrode plates are by aid of said slots adjustable bodily along said supporting arms, mechanism connected with said supporting arms for enabling said supporting arms to swing to different angles relatively to each other, spring mechanism connected with said arms for retracting the same into predetermined normal positions, means controllable by the operator for virtually lengthening and shortening said arms, and connections for energizing said electrode plates.
6. In a clamping electrode the combination of a pair of supporting arms pivotally connected together, a pair of electrodes mounted upon said supporting arms, and mechanism connected with said supporting arms and controllable by the operator for varying the distance of said electrodes from the point at which said supporting arms are pivotally connected together.
7. An electrode clamp comprising a pair of supporting arms pivotally connected together, a pair of electrode plates detachably mounted upon said supporting arms and adjustable bodily in relation thereto for enabling said electrode plates to be shifted into different positions relatively to said supporting arms, and mechanism carried by said supporting arms and controllable by the operator for virtually lengthening and shortening said supporting arms.
8. An electrode clamp comprising a pair of supporting arms, handle mechanism connected with said supporting arms for enabling the operator to shift said supporting arms angularly into different positions relatively to each other, a pair of electrode plates mounted upon said supporting arms respectively, and adjusting mechanism carried by said supporting arms and connected with said electrode plates for enabling the operator to shift the position of said electrode plates relatively to the length of said supporting arms.
9. A clamping electrode comprising a pair of supporting arms, a pair of electrode plates mounted upon said supporting arms, mechanism carried by said supporting arms for enabling the operator to turn said electrode plates into different positions relatively to the length of said supporting arms, means for energizing said electrode plates, and mechanism carried by said supporting arms and controllable by the operator for virtually changing the length of said supporting arms.
10. A clamping electrode comprising a pair of supporting arms, a pair of electrode plates supported by said supporting arms and normally facing each other, each supporting plate being adjustably revoluble upon an axis extending through the supporting arm carrying the electrode plate, and mechanism carried by said supporting arms and controllable by the operator for enabling said arms to be swung to different angles relatively to each other.
11. In a clamping electrode the combination of a pair of supporting arms, a pair of electrode plates each mounted upon one of said arms, each electrode plate being adjustable bodily along the arm upon which it is mounted and also adjustable angularly in relation to the length of said last mentioned arm, a pivotal mounting for said supporting arms, and means controllable by the operator for virtually varying the length of said supporting arms.
12. In a clamping electrode the combination of a pair of supporting arms, a pair of electrodes mounted upon said supporting arms means for energizing said electrodes, and mechanism connected with said supporting arms and controllable by the operator for varying the distance between said electrodes pivotally and also by sliding said electrodes along a straight member.
13. In a clamping electrode the combination of a pair of supporting arms, a pair of electrodes mounted upon said supporting arms, means for energizing said electrodes, mechanism connected with said supporting arms and controllable by the operator for lengthening and shortening said supporting arms, and means for enabling the operator to shift said supporting arms angularly in relation to each other.
14. In a clamping electrode the combination of a pair of supporting arms, a pair of electrodes mounted upon said supporting arms means for energizing said electrodes, and mechanism connected with said supporting arms and controllable by the operator for varying the distance between the electrodes, both by changing the angle between them and by keeping the angle between the planes of the electrodes unchanged.

Signed at Long Island City, in the county of Queens and State of New York, this 31 day of March, 1925.

FREDERICK H. WAPPLER.
